UNITED STATES PATENT OFFICE.

HENRY D. SMITH, OF CHICAGO, ILLINOIS.

FURNACE.

SPECIFICATION forming part of Letters Patent No. 531,394, dated December 25, 1894.

Application filed April 24, 1893. Serial No. 471,716. (No model.)

To all whom it may concern:

Be it known that I, HENRY D. SMITH, a citizen of the United States, residing at Chicago, in the county of Cook and State of Illinois, have invented certain new and useful Improvements in Furnaces, of which the following is a specification, reference being had to the accompanying drawing, in which the drawing is a central longitudinal vertical section 10 of a furnace containing my improvements.

My invention relates to furnaces, and has for its object to provide a furnace in which the combustion will be perfect enough to insure the combustion of all carbon so as to 15 render it practically smokeless.

To this end my invention consists in providing means whereby an abundant supply of fresh air may be introduced into the furnace, and also in providing for a better draft, 20 as will be hereinafter specified and as illustrated in the drawing.

That which I regard as new will be set forth in the claims.

In the drawing,—1 indicates a furnace, 25 which is provided with a forward combustion chamber 2 and a rear combustion chamber 3 located somewhat below the forward chamber 2.

4 indicates the grate-bars of the chamber 30 2, which grate-bars may be of any desired pattern.

5 indicates the grate-bars of the chamber 3, which are tubular, as shown.

6 indicates an upper furnace door opening 35 into the chamber 2.

7 indicates a lower furnace door opening into an ash-pit 8 under the grate-bars 4 of the chamber 2. The bottom of the ash-pit 8 is about upon a level with the grate-bars 5, as 40 shown.

9 indicates a passage leading from the ash-pit 8 to the combustion chamber 3, in which passage is a door 19.

10 indicates an ash-pit located under the 45 chamber 3 and extending forward under the ash-pit 8.

The forwardly extending portion of the ash-pit 10 constitutes a separate air conduit 10^a, arranged beneath the ash-pit 8, and adapted 50 to communicate with the external atmosphere

through the medium of a door 11. The air-conduit 10^a is cut off from communication with the ash-pit 8 through the medium of an imperforate wall 19 of any material suitable for the conditions required. As here shown 55 the imperforate wall is arranged horizontally, and it extends from the front wall of the furnace structure to the passage-way 12. The imperforate wall makes the air-conduit 10^a a separate and distinct channel for the passage 6^c of air to the hollow grate-bars 5.

12 indicates a passage way leading from the ash-pit 10 to the open ends of the grate-bars 5.

13 indicates a slide adapted to close the opening of the passage way 12, which slide is 65 operated by a rod 14 projecting through the front of the furnace, as shown; which construction provides for operating the slide 13 from the front of the furnace.

15 indicates a smoke-stack into which the 70 chamber 3 opens.

16 indicates a chamber located under the smoke-stack 15, into which chamber the grate-bars 5 open.

17 indicates a grating which forms the top 75 of the chamber 16 and serves to prevent cinders and ashes from falling into said chamber.

18 indicates a slide or door at the side of the furnace, through which access may be had to the chamber 3. 80

The fire is built upon the grate-bars 4 in the chamber 2, and after arriving at a certain point in its combustion a portion of it is pushed back upon the grate-bars 5, sufficient fuel being retained upon the grate-bars 4 to 85 provide for igniting fresh fuel. Air, passing through the ash-pit 8, serves to insure good combustion in the chamber 2, and perfect combustion of the fuel in the rear chamber 3 is secured by the admission of fresh air thereto 90 through the ash-pit 10. By this construction the air which is fed to the rear chamber 3 is fresh and not vitiated by a prior passage over burning fuel. To further provide for proper combustion the furnace is fed by a current 95 of hot fresh air which passes from the separate air-conduit 10^a through the passage 12 and grate-bars 5 to the chamber 16, and thence through the grating 17 to the smoke-stack, and any particles remaining unconsumed will 100

be caused to ignite owing to the intense heat thereby created.

If it is desired to shut off the supply of hot air it may be accomplished by moving the slide 13, closing the opening of the passage 12.

I am aware that furnaces having front and rear combustion chambers located upon different levels are not new; but in all such furnaces with which I am familiar the rear combustion chamber has been fed through the same air passage as the front chamber, there being no provision for separating the two air passages. Such constructions are inefficient in that the supply of air conducted to the rear furnace is robbed of its oxygen, and has little effect upon the fire.

That which I claim as my invention, and desire to secure by Letters Patent, is—

1. The combination with a furnace structure having a smoke conduit 15 at the rear, of an air chamber 16 located under the smoke conduit, two combustion chambers 2 and 3 arranged one in rear of the other, a passage 9 leading from the ash pit of the front combustion chamber to the rear combustion chamber, hollow air-conducting grate-bars 5 for the rear combustion chamber, connected with the air chamber under the smoke conduit, a passage-way 12 leading from the ash-pit of the rear combustion chamber to the front open ends of the hollow grate bars, an air conduit for supplying fresh air to the front combustion chamber, and a separate air conduit for supplying air to the rear combustion chamber, substantially as described.

2. The combination with a furnace structure having a smoke conduit 15 at the rear, of an air chamber 16 located under the smoke conduit, two combustion chambers 2 and 3 arranged one in rear of the other, hollow air conducting grate bars 5 for the rear combustion chamber, connected with the air chamber under the smoke conduit, a passage-way 12 leading from the ash-pit of the rear combustion chamber, substantially as described.

bustion chamber to the front open ends of the hollow grate-bars, a slide or damper 13 for closing communication between the said passage-way and the ash-pit of the rear combustion chamber, an air conduit for supplying fresh air to the front combustion chamber, and a separate air conduit for supplying fresh air to the rear combustion chamber, substantially as described.

3. The combination with a furnace structure having a smoke-conduit at the rear, two communicating combustion chambers 2 and 3 arranged one in rear of the other, and hollow air conducting grate-bars 5 for the rear combustion chamber having communication with the smoke-conduit, of a separate air-conduit 60 closed against communication with the front ash-pit and supplying fresh air to the forward ends of the hollow grate-bars, substantially as and for the purposes described.

4. The combination with a furnace structure having a smoke conduit 15 at the rear, of an air chamber 16 located under the smoke conduit, two combustion chambers 2 and 3 arranged one in rear of the other, front grate bars 4, a passage 9 leading from the ash-pit of the front combustion chamber to the rear combustion chamber, hollow air conducting grate bars 5 for the rear combustion chamber, connected with the one chamber under the smoke conduit, a passage-way 12 leading from the ash-pit of the rear combustion chamber to the front open ends of the hollow grate bars, a slide or damper 13 for closing communication between the said passage-way and the rear ash-pit, an air conduit for supplying fresh air to the front combustion chamber, and a separate air conduit for supplying fresh air to the ash-pit of the rear combustion chamber, substantially as described.

HENRY D. SMITH.
